UNITED STATES PATENT OFFICE.

BERNARD MACDONALD, OF SOUTH PASADENA, CALIFORNIA.

ACID-PROOF AIR-NOZZLE AND VALVE.

1,116,308.

Specification of Letters Patent.

Patented Nov. 3, 1914.

Application filed March 25, 1914. Serial No. 827,047.

To all whom it may concern:

Be it known that I, BERNARD MACDONALD, a citizen of the United States, residing at South Pasadena, county of Los Angeles, 5 State of California, have invented certain new and useful Improvements in Acid-Proof Air-Nozzles and Valves; and I do hereby declare the following to be a full, clear, and exact description of the invention, 10 such as will enable others skilled in the art to which it appertains to make and use the same.

This invention relates to apparatus for handling acid solutions and particularly to 15 apparatus for use in the treatment of ore pulp, slimes and the like.

In apparatus for treating ore slimes it is frequently desirable to prevent to as large an extent as possible the settling of solids 20 and thickened portions in the slimes, since if such portions of the slimes were to collect upon the bottom of the receptacle, dissolving would take place much more slowly. In order to guard against collecting of the 25 thicker portions of ore slimes it has been common heretofore to provide the receptacle for such slimes with transfer pipes through which the material is raised continuously from the bottom portion of the 30 receptacle to the upper portion thereof.

The present invention is directed to the provision of apparatus for handling acid solutions under conditions which make the use of acid-proof material desirable. The 35 apparatus comprises a transfer pipe or tube through which the material is forced and a nozzle for compressed air positioned for forcing the acid solution through the transfer pipe, these parts being made of wood 40 so as to be proof against attack by the acid.

The invention involves the provision of a novel form of compressed air nozzle which is of marked simplicity in construction, which is reliable and efficient in operation, 45 the parts of which may be readily manufactured and assembled at low cost and which permits of the use of acid-proof material throughout.

The invention also involves an improved 50 method of mounting the nozzle upon its support in co-operative relation to the transfer pipe and improved means for making connection from the compressed air pipe to the nozzle.

55 These and other features of the invention

will be better understood by reference to the following description taken in connection with the accompanying drawings which show the preferred embodiment of the invention.

In these drawings, Figure 1 is a central section of a tank for treating ore slimes. Fig. 2 is an enlarged view in section through the nozzle and the lower end of the tank and transfer pipe. Fig. 3 is a detail view in 65 horizontal section on line 3-3 of Fig. 2 showing the connection of the air supply pipe to the nozzle.

Referring to these drawings, A indicates a tank of substantial size preferably constructed of wooden staves and mounted on a suitable base B. Within the tank A are a plurality of transfer pipes C each arranged in a vertical position. Each of these pipes is supported upon the bottom D of the tank in any suitable manner with its lower end a short distance above the bottom D. In the drawings each pipe is shown as mounted upon four uprights d rising from the bottom of the tank and having their 75 upper ends secured to the lower end of the pipe C. The solution in the tank is forced upwardly through the pipes C and out through outlets e near the upper end of the pipes C. These outlets are disposed parallel 80 to the adjacent side wall of the tank so that the discharge therefrom causes the material in the tank to take up a circular motion, as indicated by the dotted line in Fig. 1. This circular motion of the material aids in retarding the settling of the thicker portions 85 of the solutions.

The material is caused to flow upwardly in the pipes C by compressed air admitted to the lower ends of the pipes. For this purpose nozzle E is provided. This nozzle, like the pipes C, is made of wood so as to be proof against attack by acid in the solution. The nozzle is circular in cross-section and a portion of it is tapered as shown at e. A 95 tapered opening is provided in the bottom D of the tank for the reception of the nozzle E, and the nozzle is mounted in position by passing it upwardly through the opening in the bottom of the tank until the tapered portion e engages and wedges against the wall of the tapered opening in the bottom of the tank. In this way the nozzle may be quickly mounted in position in such a manner as to 100 preclude leakage around the nozzle, and also 105 110

the nozzle may be readily withdrawn when its withdrawal is desirable for the purpose of inspection or repair.

The nozzle has a central opening there-
5 through, as is indicated at e^2 . Near the up-
per end of the nozzle this opening is en-
larged in cross-section as is shown at e^3 , the
enlargement of this central opening extend-
ing to the upper end of the nozzle. This
10 enlargement of the opening through the nozzle
provides a seat for a valve in the form
of a ball F. This ball is made of non-metal-
lic material. Preferably the ball is glass or
earthenware, and its surface is made so
15 smooth that the valve will seat itself accu-
rately upon the wall at the junction of the
passage-way e^2 and the enlargement e^3 . The
wall of the nozzle above the seat for the
valve is provided with a plurality of trans-
20 verse openings e^4 . The upper end of the
enlarged portion e^3 of the passage-way
through the nozzle is threaded to receive a
plug e^5 , which constitutes a retainer for
holding the ball valve F in its position with-
25 in the nozzle. This retainer, however, per-
mits such upward movement of the ball F
as will allow the air to pass freely from the
passage-way e^2 through the transverse pas-
sage-ways e^4 .
30 When the nozzle is mounted in position as
above described, its upper end is close to and
preferably slightly within the lower end of
the transfer pipe C. An air supply pipe G
is connected to the lower end of the nozzle
35 E below the bottom of the tank. The end
of this pipe G is secured to a metallic plate
g curved to correspond with the curvature
of the nozzle E and having an opening alin-
ing with the opening in the pipe G. A bail
40 g' is adapted to encircle the nozzle, its ends
passing through the ends of the plate g and
having nuts on the ends thereof by which
the bail and the plate g may be caused to
grip the nozzle E firmly. The nozzle has a
45 transverse opening therein leading to the
passage-way e^2 with which the opening in
the plate g alines when the parts are assembled
in the manner shown in Figs. 2 and 3. The
opening e^2 extends all the way to the bot-
50 tom of the nozzle and a plug g^2 is provided
for closing the lower end of the passage-
way. This plug may be readily withdrawn
to permit of clearing the passage-way e^2 of
particles which may become lodged therein.
55 In operation, the compressed air passes
from the pipe G into and through the nozzle
E, raising the valve F and issuing
through the transverse openings e^4 . The air

issues from the nozzle thus intermittently
forming a series of air pistons as indicated 60
in Figs. 1 and 2, separated by bodies of the
solution which enter the pipe C at the lower
end thereof.

I claim:

1. The combination of a wooden pipe, 65
means for supporting the same on end, a
wooden nozzle mounted in an upright position
with its upper end within and close to
the lower end of the pipe, said nozzle having
70 a central passage therethrough which is en-
larged in diameter near its upper end to
provide a valve seat at the lower end of the
enlarged portion of the passage and said
enlarged portion extending from the said
75 seat to the upper end of the nozzle, trans-
verse openings in the wall of the nozzle
above the valve seat, a ball valve of non-
metallic material located in said enlarge-
ment and coacting with the valve seat, and
a retainer threaded into the upper end of 80
the passage through the nozzle.

2. The combination of a support having
a tapered opening therein, a wooden pipe
mounted in an upright position over said
opening and having its lower end open, a 85
wooden nozzle extending through the opening
in said support and having the exterior
thereof tapered to wedge in said tapered
opening, said nozzle being in alinement with
the pipe and having its upper end adjacent 90
to the lower end of the pipe, and a valve in
the nozzle controlling the passageway there-
through.

3. The combination of a support having
an opening therein, a wooden pipe mounted 95
in an upright position over said opening
and having its lower end open, a nozzle
mounted in the opening in said support with
its upper end adjacent to the lower end of
the pipe, a compressed air pipe below said 100
support, a plate secured to the end of the
pipe and lying against the lower end of the
nozzle, and a bail encircling the pipe and
having its ends secured to the ends of the
plate, said nozzle having a passageway 105
therethrough the lower end of which ex-
tends transversely and coacts with an open-
ing through said plate leading to the in-
terior of the compressed air pipe.

In testimony whereof I affix my signature, 110
in presence of two witnesses.

BERNARD MacDONALD.
